UNITED STATES PATENT OFFICE.

ROBERTO TAEGGI PISCICELLI, OF NAPLES, ITALY.

TICKET-PUNCH.

No. 801,607.

Specification of Letters Patent.

Patented Oct. 10, 1905.

Application filed October 13, 1904. Serial No. 228,288.

To all whom it may concern:

Be it known that I, ROBERTO TAEGGI PISCICELLI, a subject of the King of Italy, residing at Corso Umberto I, No. 23, Naples, in the 5 Kingdom of Italy, have invented certain new and useful Improvements in Ticket-Punches, of which the following is a specification.

This invention relates to machines for punching tram and similar tickets.

It is the usual practice to collect in a single box the disks cut from tickets sold, and to obtain the total amount of the sale it is necessary to count at the end of each journey or of each day the disks so collected in the box, 15 after sorting them according to their colors. In order to avoid the necessity of this operation, the machine which forms the object of the present invention is provided with as many compartments as there are colors—that 20 is, prices of the tickets—and each compartment has a counter, which counts the disks falling into it. By this arrangement the counting of the disks is mechanically performed. The machine is further provided with a locking device which prevents its working when 25 the actuating-bar is pulled by mistake without a ticket being inserted.

In the annexed drawings I have shown a form of construction of said machine intended 30 for tickets of four different prices.

Figure 1 is a front view; Fig. 2, a section on the line A B of Fig. 1, and Fig. 3 a rear view of the machine. Fig. 4 shows the interior. Fig. 5 is a section on the line C D of 35 Fig. 4. Fig. 6 is a front view of the inner box. Figs. 7, 8, and 9 show details of the counters. Fig. 10 shows a detail of the locking device.

1 is a circular casing without a cover and 40 having in its bottom an opening 2, which occupies an entire quadrant. In the center of the box is a stud 3, on which rotates a sleeve 4, fast with circular box 5, divided by a diaphragm into a front and a back part, this latter being divided, by means of radial partitions 6, into four compartments, corresponding to the four kinds of tickets. On the outer surface of the front compartments are shown the colors and the prices of the tickets. Each 45 compartment is closed at the back by a movable shutter 7, which can be removed by bringing the compartments over the opening 2 and raising the locking-bar 8, thus allowing the disks to be emptied from the compartment. 50 The disks fall into their respective compartments through holes 9, formed in the wall of

the box 5, these holes being brought under the punch as follows: The box is provided with a spring-button 10, sliding on a lug 11. The inner end of the button carries a knob 6c 12, which when the button is in its normal position is in the plane of four stops 13 on the periphery of the casing 1, so that the displacement of the box 5 is limited between two successive stops; but by pushing in the button 10 the knob 12 can be brought below the stops 13 and the box may be turned through any desired arc. The box is, however, provided with a spiral spring 14, tending to rotate the box in the opposite direction to that 65 indicated by the arrow in Fig. 1. It is therefore obvious that by pressing the button 10 and then turning the box in the direction of the arrow until the button is brought between two successive stops—for instance, between 70 13² and 13³—as soon as the button is let free the spring will carry the box back into the position shown in Fig. 1, so as to bring the knob 12 to rest against the stop 13². In this position the hole 9 under the punch is that in 75 80 the compartment for the twopenny-tickets. The movement of the box is limited by the stops 13' and 13⁴.

The perforation of the tickets is performed by means of a punch 15, connected with a lever 16, which can be depressed by pulling down a hook 17 at the end of a bar 18, sliding in guides fixed on the bottom of the casing. The punch is normally held in its raised position by a spring 19. A cap 20 is provided to cover the punching device. On pulling down the bar 18 a toothed spring 21 upon it meets the short arm of a bell-crank lever 22, the longer arm of which is fitted with a hammer, which when the tooth 21 leaves the short 95 arm of the lever free strikes against a bell 23.

The ticket to be perforated is introduced between the plate 24 and the under side of the supporting-lug 25 and pushes back the free end 26 of a lever pivoted on a pin 27, Fig. 10. 100 This lever is fitted with a locking-pin 28, which normally engages a hole in the bar 18. As the lever is pushed back the pin is withdrawn from the hole and the bar 18 is freed and can actuate the punch. When the bar 18 under the action of the spring 19 rises again to its normal position, a spring 26' urges the lever 26 against the bar 18 and causes the pin 28 to again enter the hole in the bar 18, and thus the latter remains locked until another 105 ticket is introduced.

As the ticket is perforated a lever 29, con-

- 5 nected to the bar 18, rocks a shaft 30, and an arm 31 upon it strikes against one of the levers 32, which by means of a pawl 33 rotates a ratchet-wheel 34, fast with a disk 35, bearing on its face the numerals from "0" to "9." This disk is the first of a counting-train, and its movement is communicated in the usual manner by means of an arm 36 and a star-wheel 37 to the next disk 38, and so on.
- 10 The disks and the wheels of the counters are contained in the front part of the box 5, and the cover 39 is provided with openings 40, through which the number of the tickets issued can be read.
- 15 To restore the counters to zero, there is provided beneath each disk a toothed wheel 41, turning loose on the stud 42, on which the disk is mounted. All the wheels 41 mesh the one with the other and are put in movement by 20 means of a pinion 43, which can be turned by means of a key after removing the shutter 7. Each wheel 41 is fitted with a pawl 44 and each arm 36 with a pin 45. When the disks rotate under the action of the levers 32, the 25 pins 45, turning in the direction of the arrows, Figs. 7 and 9, raise the pawls 44 and pass under them without producing any effect. If, however, the wheels 41 rotate in the direction of the arrows under the action of the pinion 30 43, the faces 46 of the clicks 44 come against the pins 45 and carry them and the disks round in such a way that after turning the key as many times as is required all the disks will have been restored to zero.

The box 1 is provided with lugs 47, holes 35 through which can be passed the ends of a cord for suspending the punch.

Having now particularly described and ascertained the nature of my said invention and in what manner the same is to be performed, 40 I declare that what I claim is—

1. A ticket - punch, comprising a case, a punch carried thereby, a movable box divided into several compartments, and means for turning the box, substantially as described. 45

2. In a ticket-punch, the combination of a casing, a punch carried thereby, and a movable box having several compartments each fitted with a counter, substantially as described. 50

3. In a ticket-punch, the combination of a casing, a punch carried thereby, a movable box, a spiral spring connecting the box to the casing, and means for locking the box in any desired position, substantially as described. 55

4. In a ticket-punch, the combination of a hooked sliding bar, actuating the punch, a pin engaging a hole in the bar, a lever carrying said pin, and actuated by the insertion of a ticket to disengage the pin from the bar, substantially as described. 60

In testimony whereof I have affixed my signature, in presence of two witnesses, this 14th day of September, 1904.

ROBERTO TAEGGI PISCICELLI.
